Solomon Dickinson

The schedule referred to in these Letters Patent and making part of the same, containing a description in the words of the said Sol
~~mon Dickinson himself of his improvement in cooking Stoves.~~

Specification of Solomon Dickinson's New and useful Improvement in cooking Stoves for burning wood or coal.

In general form, it is an upright oblong - similar to other modern cooking Stoves, on its front aspect. It consists of eight plates viz. a top having perforations to admit kettles, boilers, &c. A bottom plate - ~~one~~ ^{one} extending beyond the front and sides of the stove, to afford room for convenience of heath whilst cooking, two side plates with two doors in each, a front plate, the lower part of which contains the bars for a grate, and its upper part, in connexion with the sides and back, forms the front oven, immediately behind which is a semicircular box, narrower than the front, and attached to the upper and back part of the oblong front oven, constituting another and more spacious oven, resting upon a leg at its back extremity the whole enclosed and covered by the top plate with its perforations. The hearth plate is sunken under the stove, and forms a shallow box, immediately underneath the fire, extending from one extreme side to the other and so situated, that it must receive the ashes and whatever else, that falls from the consuming materials within the grate, at each extremity of this sunken box, and immediately outside of the doors, in the side plates, at which the fuel is introduced, are ledges, upon which a square plate rests, whose upper surface forms a level in union with the hearth. When this plate is removed a grid-iron can be substituted for purposes of boiling &c. &c. Between the front oven and the semicircular box, is the middle plate, dividing the oven of said box, and forms a part of the front oven, this division plate inclines diagonally backwards, so as to give a considerable space to the front, in which

is the fire. This space can at all times be contructed by two additional plates called sliders. They must be long enough to reach from one side of the stove to the other, and their ends resting upon two projecting ledges formerly attached to the side plates, without and immediately at the lower part of the upper doors, in the side plates, each slide extending transversely upon the ledges separating the space occupied by the fire, beneath, and forming by such division the bottom of the front oven. The sliders must be braced at the edges of their junction, so as to lay over each board, and form one entire plate, and when baking is required in both ovens, and the boilers not in use, they are spread out to their utmost extent, but when heat is to be applied to the boilers either in front or back or back, the sliders must be slipped together, leaving an opening their whole length, regulated more or less as occasion requires, either at the front or back of the oven, for the heat to pass thru, a ridge runs along the whole length of the sliders to prevent their being slipped over one another too far, and acts as a gauge to the regulation for the heat. In the middle of the incline division plate, is a transverse cut, or opening at the segment of the semicircular box, immediately beneath the sliders, and a similar one in the upper extremity of the plates, these cuts or openings can be closed at pleasure by an extension below, passing up and down, to cover either cut, when the heat is to shut out, from passing thru it. The lower opening forms a vacuum, for the passage of heat and smoke, between two plates, one is the bottom of the semicircular box, and the other is a false plate, placed just above the transverse cut, so as to form the vacuum, and is the bottom of the oven of the semicircular box. When it is desirable to shut down the oven, upon the lower transverse cut, the upper cut is conveniently opened, the heat and smoke readily will pass into the oven, and surround the boiler upon the top of the

8991X

semicircular box, and afterwards discharges itself, then another opening at the upper and back part, and within the oven, entering at the fire, where also is placed another valve to command the escape when the heat is required to pass thru the vacuum below formed by the two plates at the bottom of the semicircular box, and which has a scraper affixed behind it, to clean out the soot occasionally. The grate to contain fuel may be made of perpendicular bars, and attached to the plate in front, or cast with it, and another grate made separately, and placed horizontally, over the sunken box of the hearth to be raised or lowered at pleasure, so as to diminish or increase the quantity of fuel. this grate will form the bottom of the fire place, as in general use in the ordinary stove. The improvements of the above invention, which are new, and for which I now claim the exclusive privilege of a patent, are the slides, the large valve with the cuts or openings, in the diagonal plate, and the passage for the heat, and smoke, caused by the cuts, and in the vacuum below, in the semicircular box. These constitute my claims, and have never to my knowledge or belief been heretofore applied to the purposes of cooking, certainly have never been seen or heard of before by me.
